MULTIPLE FUSE DEVICE

William H. Frank, Joseph A. Messing, and Harrison J. L. Frank, Detroit, Mich., assignors to Bulldog Electric Products Company, Detroit, Mich., a corporation of West Virginia

Application April 19, 1933, Serial No. 666,786

17 Claims. (Cl. 290—126)

This application relates to circuit protective devices, and particularly to those commonly known as multiple fuse devices.

It has been proposed in the past to provide for circuit protection, a plurality of fuses mounted on a rotatable body element so that one after another of the fuses may be brought into and electrically connected to the line as a preceding fuse blows out. The rotating body element of the circuit protecting device is generally made of insulating material and generally has barriers, etc. as considered desirable by the designer.

One principal object of the invention is to provide, as the rotatable body element of such a device, a substantially flat wheel, including a wheel proper, of insulating material having mounted thereon circumferentially spaced, radially positioned fuses. This design of body element has proven of value per se, and also in connection with circuit protective devices of novel design which will more specifically be illustrated in other applications, these relating more specifically to mechanisms for rotating and electrically connecting in circuit the body element or wheel.

Still further objects are the provision of novel details of construction of body elements of multiple fuse circuit protective devices.

A still further object is to provide a standard fuse wheel constructed so as to be adapted for use in a number of different ways, and for various amperages and voltages.

A still further object is to provide a fuse wheel composed principally of insulating material having steel or other metal enclosed parts for providing suitable tensile strength for the wheel.

A still further object is the provision of a body element of the character specified which is so arranged that the gases which arise incident to the blowing of a fuse are expelled into explosion chambers, from where these gases are conducted, through vent passages to a central large expansion chamber or exhaust manifold and then to the atmosphere. In one embodiment of the invention these vent passages have tapered ends, where they discharge into the central chamber, and in these ends are disposed tapered plugs of suitable material, such as cement, plaster of Paris, etc. These plugs prevent the gases discharged by one blown fuse from entering the vent connected to a chamber in which an unblown fuse is disposed. However when a fuse blows out, the plug which corresponds to that fuse is itself blown out in the direction of enlargement of the tapered vent to release the gas pressure in the explosion chamber and in the vent connected thereto.

It will also be observed that, for all the explosion chambers of the fuses, there is provided a common exhaust manifold or expansion chamber.

This eliminates the necessity of providing for each

fuse, a separate expansion chamber, and promotes economies of space, etc. Further, the expansion chamber need not be in the replaceable part of the device, namely the wheel, but may be in the casing of the device, the non-replaceable part. This promotes economies of space, etc. as well as of manufacturing cost, insofar as the replaceable and necessarily inexpensive part of the device, the wheel, is concerned. 5

It will also be observed that the fuses are in part encased in discs which are embossed into place so that all of the parts of the wheel will be tightly locked in place and thus rendered immovable on the wheel, thus insuring against parts becoming misplaced and affecting the operation 15 of the device, or causing short circuits, etc. The discs further render the wheel substantially gas tight, to insure against arcs and hot gases injuring surrounding objects or causing electrical flashovers. 20

It is also an object of the present invention to provide a rotating body upon which are positioned a number of fuses all of which are relatively independent, as contradistinguished from prior constructions wherein a number of fuses 25 are provided in the form of arms radiating from a central hub, all formed as one piece of fuse material. In prior art constructions, the blowing of one fuse often causes all of the fuses to blow, since they all are connected, structurally, 30 thermally, and electrically. In the instant construction, where the fuses are structurally, thermally, and electrically independent, this cannot occur. 35

Further, the instant fuses have wide ends, for contact making purposes, and narrow central parts, which are the fusible parts. These central parts are S shaped so that their electrical paths will be as long as possible, consistent with their overall length being relatively small, it being observed that longer fuse paths are apt to have a smaller percentage of variation, in electrical characteristics, than shorter fuse paths of equivalent resistance or calibration. However, in proportioning the fuses, recognition is taken of the fact that short fuses offer greater heat conductivity (less heat resistivity) and more nearly uniform temperature gradient than similar, but longer fuses. In other words, the fuses are proportioned 40 so as to balance the desire for length of fuse path, for uniformity of characteristics, against the desire for shortness of fuse, for thermal conductivity. 45

A still further object is the provision of a novel fuse, including a strip of a suitable fuse metal, upon which is a plating of copper, the latter having the useful function of providing a more suitable contact or terminal surface than is provided by the fuse metal, it being observed that copper 50

has a higher electrical and thermal conductivity than is possessed by the fuse metal itself.

It will further be observed that the contact part of each fuse is isolated and shielded from the critical part of the fuse, namely the part within the explosion chamber and which is apt to fuse on overload. This isolation and shielding prevents the heat of explosion, or the vapors thereof, from escaping from the explosion chamber, except thru the proper vents, etc. and specifically insures them from reaching the contact or terminal ends of the fuses.

The wheel or body element per se is preferably made of an insulating material which has a high heat conductivity, glazed or unglazed porcelain, plain or pyrex glass, etc. having proven practical. Such materials transfer heat from the fuses very rapidly and thruout the entire wheel or disc.

Further, in one embodiment, as where the expansion chambers are in the wheel itself, these chambers are loosely stuffed with a finely divided heat absorbing material, such as gravel, fine silicates, glass wool, etc. these also providing a tortuous but free path for the escape of gases.

The use of glass wool is particularly desirable since this material has high heat absorbing qualities, and acts as a deionizing or arc quenching agency. Further, the material may be used to pack the explosion chambers.

Still further objects of the invention will presently appear upon reference to the following detailed description of embodiments of the same, which embodiments are disclosed in detail in the accompanying drawings.

In these drawings Fig. 1 is a transverse section as if on line 1—1 of Fig. 2, of one form of wheel or body.

Fig. 2 is a cutaway elevational view of the same.

Fig. 3 shows in cutaway perspective a fuse used in the embodiment of Figs. 1 and 2.

Fig. 4 is an elevational view of the wheel of Figs. 1 and 2 to reduced scale.

Fig. 5 is a transverse section as if on lines 5—5 of Fig. 6 of a second form of wheel or body.

Fig. 6 is a partial cutaway elevational view of the same.

Figs. 7 and 8 are transverse sections of other modified forms of wheels or bodies.

Fig. 9 is a transverse section of still another wheel or body, as if on line 9—9 of Fig. 10.

Fig. 10 is a partially cutaway elevational view of the same.

THE WHEEL OR BODY

Figs. 1—4

The various forms of wheels or bodies and their component parts, disclosed in Figs. 1 to 10, will now be described specifically.

The wheel or body of Figs. 1 to 4 includes a flat wheel proper 10, of suitable insulating material, such as porcelain, etc., provided with a large central hole or exhaust manifold 11, from which radiate outwardly a number of equally spaced radial slots 12. In radial alinement with each slot, and projecting from each face of the wheel is a boss 14 and between the slots 12 are radially inwardly projecting fingers 15. The outer periphery of the wheel, beyond the bosses 14, is referenced 16.

Disposed in the outer end of each slot 12 and passing from one peripheral edge of the wheel proper, over the boss 14 on the adjacent face, and then through the slot 12, over the boss 14 on the opposite face of the wheel proper, and

to the adjacent peripheral edge of the wheel proper, is a fuse element 17, formed from a flat fuse strip of the form of Fig. 3. As indicated, all of the fuses are separate and independent, and relatively isolated. The terminals 5 or contact parts of the fuse, that is to say, the ends 18, are on the faces of the wheel over the bosses 14 and are of substantial and equal width, as indicated, whereas the central part 19, of the fuse which is the part that blows on overload, 10 is in the form of a narrow ribbon, having S shaped ends, as indicated. The fuses are made from a strip of suitable fuse material such as zinc, alloy, etc. and are preferably copper plated or electroplated as indicated best in Fig. 3, so 15 that the ends 18 will have high thermal and electrical conductivity, as they engage the associated fixed contacts of the device.

On the faces of the wheel proper are fibre discs 20, these having apertures 21 receiving, and 20 through which project the bosses 14, and the portions 18 of the fuses 17 thereon, and also having their outer peripheral edges projecting beyond the wheel proper periphery 16 and deformed inwardly as indicated at 22, so that adjacent peripheral edges of the discs 20 may be brought together and encircled by a metal ring 23 of channel cross-section which binds the discs, the fuses and the wheel proper, in assembly.

The channelled ring 23 may be provided with 30 suitable indicia as indicated best in Fig. 4, corresponding to the locations and numbers of the fuses 17. For the wheel shown, where there are twelve pairs of bosses and therefore twelve fuses, the ring will be numbered from 1 to 12, each 35 number corresponding to one of the fuses.

As indicated in dotted lines, the edges of the apertures 21 of the fibre discs 20 through which the bosses 14 and the fuses 17 project, are normally deflected out of the planes of the discs 40 and during the assembly of the discs on the wheel proper, these edges are embossed or forced into the planes of the discs so that an extremely tight and rigid connection between the discs and the wheel proper is assured. These edges 45 also isolate and shield the portions 18 of the fuses from the portions 19 thereof, for reasons previously expressed.

On the faces of the discs 20 are disposed dished metal plates 24 covered on their outer surfaces by fibre plates 25 whose edges are turned in over the edges of the metal plates as indicated. These plates 24 and 25 are so formed that the outer edges of plates 25 engage the discs 20; their inner portions however are substantially 50 distant from the discs 20 so that a large flat expansion space will be provided between each set of plates and the adjacent disc. The flexibility of the discs provides spring pressure for facilitating assembly of the device.

The discs 20 and the plates 24—25 are centrally apertured in alignment and through these apertures there passes a tubular hub 27 having an outwardly directed flange 28 adapted to bear against one of the fibre plates 25. The end of 65 the hub 27 opposite that end thereof provided with flange 28, is, in the assembly operation, peened or riveted over a plate 29 which engages one of the fibre plates 25, and the rigid assembly of the parts is maintained by the co-operation between the plates 24—25 and the heads 28—29 of the hub, it being observed that the central hole edge 30 of each plate 25 is inwardly extruded or flanged to act as a bearing on the hub, and to insulate the adjacent plate 24 from 75

the hub 27, these metal plates being completely out of contact with any other part of the assembly other than the fibre plates 28.

The hub 27 has a vent hole 32 which connects the exhaust manifold or central hole 41, into which opens the explosion chambers, or slots 12, with the interior of the hub, so that gases which rise incident to the blowing of a fuse may escape from the entire wheel assembly through the hollow hub, and into expansion chambers 33 formed in the walls of the casing 34 containing the wheel, this feature resulting in space economies, as has been previously mentioned. Also for venting purposes, the center holes 35 of the discs 20, through which holes pass the hub 27, may be formed square as indicated, the outer diameter of the hub 27 being equal to the side dimension of each squared hole 35 so that a fairly tight fit between the discs 20 and the hub is assured, the corners of the squared holes 35 serving to connect the exhaust manifold or center hole 41 with the expansion chambers or flat spaces between the discs 20 and the adjacent sets of plates 24-25.

It will be observed that the fingers 15 act as barriers between the explosion chambers or slots 12, and that discs 20 bear tightly against these barriers to isolate the slots relatively.

It will also be observed that the assembly shown in Figs. 1 to 4 is a compact, rigid assembly whose parts are completely insulated as they should be, and whose only exposed metal parts, other than the hub 27 and the ring 23 are the terminal or contact portions 18 of the fuses 17 which lie upon the bosses 14.

Further it will be observed that the assembly is so constructed that suitable venting of the explosion gases is provided through the medium of the hub 27 and the squared holes 35 in the discs 20.

Still further it will be observed that the assembly of Figs. 1 to 4 can be effected economically and expeditiously, resulting in a highly satisfactory multiple fuse body of convenient form and of so low a cost that replacement of one body by another, after the provided number of fuses have been blown, is an inexpensive as well as a simple matter, as will be more readily brought out in a later part of this specification.

Figs. 5 and 6

In Figs. 5 and 6 there is shown a wheel or body resembling the wheel or body of Figs. 1 to 4, differing materially in that paralleling of fuses is provided. The wheel of Figs. 5 and 6 includes a wheel proper 40 having a central hole or exhaust manifold 41 provided with radial slots or inner explosion chambers 42 projecting therefrom, radially and outwardly. There is also provided in alignment with each slot 42, a radial and peripheral cutout 43 and between each cutout 43 and its adjacent slot 42 are the bosses 44, one each of these projecting axially of the wheel from each face thereof.

Around the bosses are disposed the fuses 45 and 46, the fuse 45 projecting from one boss through a slot 42 to the other boss, and the fuse 46 projecting from a boss 44 through the cutout 43 to the other boss, the terminal or contact ends of the fuse 46 overlapping the ends of the fuse 45 as indicated.

In the central hole 41 there is disposed an insulating cylinder 47 against which the ends of the barriers between the slots 42 bear, the cylinder closing each slot from the central hole.

On opposite faces of the wheel proper 40, are fibre discs 50 having holes receiving the bosses and the projecting parts of the fuses 45-46 and having flanged edges 51. The discs 50 also have holes 52 aligned with the slots 42, and radially outside of the cylinder 47. The edge 51 of one disc 50 overlaps and receives the edge 51 of the other disc 50, and the inner edge 51 is slightly clear of the peripheral edge of the wheel proper. Binding the periphery of the wheel and encircling the flanges 51 are the annuli 53, each of which includes a metal plate 53a and a fibre plate 53b enshrouding the metal plate 53a. The edges of the annuli 53 are flanged, as indicated at 54, with one flange 54 overlapping and receiving the other flange 54. Wire staples 55 are passed through the flanges 54 and 51 and are clinched over against the periphery of the wheel proper to bind the discs 50 and the annuli 53 to one another, and in place, and rivets 56 are passed through the annuli 53, the discs 50 and holes 57 in the portions 58 of the wheel proper, between the cutouts 43.

It is observed at this time that the portions 58 continue radially inwardly towards the center hole 41, and form barriers between the slots 42 and cutouts 43.

The central part of the assembly includes central plates 60-61, respectively of metal and fibre, a hub 62 provided with a head 63 and a separate plate 64 over which one end of the hub is riveted. The hub has a vent hole 65 connecting the exhaust manifold or central hole 41 with the interior of the hub.

It is observed here that the center holes of the discs 50 may be squared as shown at 66 so as to connect hole 41 with the space 67 inside of plate sets 60-61 for venting purposes.

It is also observed that the flange 54 is provided with suitable indicia to indicate the stations or positions of the respective fuses.

The construction of Figs. 5 and 6 provides at each station, two fuses 45-46, arranged in parallel so that a parallel connection between a contact on one side of the wheel assembly and a contact on the other side of the wheel assembly is effected, this feature permitting heavier loads to be carried than would be the case if but one fuse 45 or 46 were used at each station.

Because of the use of two fuses, both of which may blow, the slots 42 and the cutouts 43 have been provided to act as explosion chambers at each station, it being observed that the slots 42 open indirectly and tortuously to the manifold or central hole 41 thru the holes 52, the spaces 67, 55 the holes 66, and the hub hole 65, whereas the explosion chambers 42 open to a common race or exhaust manifold which comprises the clearance space between the periphery of the wheel proper and the inner flange 51 of a disc 50, such clearance space being formed in part, by the provision of grooves 68 in the peripheral edges of the radial barriers 58 between cutouts 43. It is observed that the hot gases and fuse metal vapors, emitted thru openings 52, are directed against the cool metal plates 60. This has the effect of deionizing the gases, and also causes the hot metal vapors to deposit their metal particles upon the plates 60, which insures against these particles being thrown into contact with such parts of the device, as would create conduction between external contacts.

Figs. 7 and 8

In Fig. 7 there is shown in transverse section

a wheel or body assembly which differs from the wheel or body assembly of Fig. 1 only in that between the plates 70—71 (equivalents of plates 24—25 of Fig. 1) and the wheel faces are insulation discs providing laminated insulation constructions as superior equivalents of the fibre discs 20 of Fig. 1. These insulation constructions include, for example, a pair of mica discs 72, a pair of asbestos discs 73 next adjacent, a pair of fibre discs 74 next adjacent, a second pair of mica discs 75 next adjacent, and a second pair of asbestos discs 76 next adjacent. In other respects the parts are like the correspondingly referenced parts of Fig. 1.

In Fig. 8 there is shown a construction which is also similar to the construction of Fig. 1, but wherein the discs 20 of Fig. 1 are replaced by sets of discs of mica 80 and asbestos 81, and wherein the space between these sets of discs, and also the space between these sets of discs and the plates 82—83 (equivalents of plates 24—25 of Fig. 1) are filled with a granular insulating and heat absorbing material, such as loosely packed gravel, coarse silicates, glass wool, etc. The discs 80—81 have squared holes similar to those provided for the disc 20 of Fig. 1 so that venting of gases from the fuses 17 to the atmosphere, through the vent holes 84 in the plates 82—83 is assured, it being observed that the course of the gases is tortuous and is through the granular insulation, as indicated by the arrows.

Figs. 9 and 10

In Figs. 9 and 10 there is shown a slightly different construction, one wherein the wheel proper 90, is of a transparent insulation material, such as glass. This wheel proper is provided with a large central hole or exhaust manifold 91 from which slots 92 project radially outwardly. In radial alignment with each of these slots is a hole 93 and separating the end of each slot with the adjacent hole 93 is a section which provides two bosses 94, projecting from each face of the wheel proper. The fuse 95 is positioned over the bosses and the narrow part 96 of the fuse projects through the wheel 90 from the boss on one face to the boss on the other, the hole 93 acting as an explosion chamber.

Opening into each hole 93 is a vent or duct 97 which opens into the exhaust manifold or central hole 91 in an enlarging taper 98. This tapered portion of each vent 97 normally contains a tapered plug 99 of cement, plaster of Paris, glass wool, etc., so constructed that it will crumble when the plug is blown out of the tapered end of the vent by the blowing of a fuse in an explosion chamber 93, the plug material once crumbled, being dissipated through the clearances and through the central hub whose interior is in communication with the exhaust manifold.

It is observed that these plugs act as barriers or one-way valves between one explosion chamber and another so that when a fuse blows, the gases escaping from the chamber containing that fuse do not reach any other explosion chamber containing an unblown fuse, the taper of the plug and the portion 98 preventing the plug from being blown into the vent and crumbled when any fuse other than the one associated with the plug is blown.

Each face of the wheel proper is covered with an asbestos disc 102 whose peripheral edge is disposed in the annular corner formed between the adjacent face of the wheel proper and the overhanging edge 103 of the wheel periphery and

these discs serve to close the explosion chambers 93 and ducts 97 at all points. The assembly of parts is maintained by means of rivets 104 passing through fibre enshrouded metal plates 105, the discs 102, and the rivet holes 106 in the wheel proper.

The central part of the wheel includes a fibre enshrouded metal plate 108, similar to the plates 24—25 of Fig. 1, and also includes the usual hub 109.

It will be seen that the condition of any fuse can be observed by viewing the fuse through the annular edge of the wheel proper 90. Further, the tapered plugs 99 may be of a color contrasting with that of the neighboring parts of the assembly, so that the presence or absence of one of these plugs would indicate whether or not the fuse associated therewith has been blown.

Now having described several embodiments and combinations, reference will be had to the following claims for a determination of the scope of the invention, it being observed that the foregoing embodiments and combinations have been chosen merely for purposes of illustration.

We therefore claim:

1. In a multiple fuse device, a fuse carrier comprising a substantially flat disc-like body of insulating material, and circumferentially spaced fuses projecting thru the body from side to side thereof and having exposed contact ends on the flat sides of the disc-like body, the body having a plurality of explosion chambers, one for that part of each fuse that is in the body, the chambers communicating with a center hole in the body that acts as an explosion manifold.

2. In a multiple fuse device, a fuse carrier comprising a substantially flat disc-like body of insulating material having thru slots connecting the flat sides of the body, fuses having their central parts in said slots and having exposed contact ends projecting therefrom and lying on the flat sides of said body, the slots extending radially from a large central thru hole in said body.

3. In a multiple fuse device, a fuse carrier comprising a substantially flat disc-like body of insulating material having thru slots connecting the flat sides of the body, fuses having their central parts in said slots and having exposed contact ends projecting therefrom and lying on the flat sides of said body, the slots extending radially from a large central thru hole in said body, and discs of insulation on the flat sides of said body and forming side closures for said slots, and retainers for said fuses.

4. In a multiple fuse device, a fuse carrier comprising a substantially flat disc-like body of insulating material having thru slots connecting the flat sides of the body, fuses having their central parts in said slots and having exposed contact ends projecting therefrom and lying on the flat sides of said body, the slots extending radially from a large central thru hole in said body, and discs of insulation on the flat sides of said body forming side closures for said slots and retainers for said fuses, the contact ends of the latter being exposed thru holes in said discs.

5. In a multiple fuse device, a circular body having a central hole, two series of radial thru slots, one series extending outwardly from said hole, and one series extending inwardly from the periphery of said body, fuses in said slots and having contact ends on the faces of said body, an insulating covering on the periphery of said body for enclosing said slots and the parts of

- the fuses therein, the covering being clear of the body so that the slots of the outer series are in relative communication thru the annular clearance.
5. In a multiple fuse device, a body having thru slots containing fuses, insulating sheets on the faces of said body enclosing said slots and providing walls for explosion chambers including said slots, and a filling for said chambers comprising comminuted refractory materials, providing tortuous paths for the escape of gases generated in said chambers incident to the blowing of fuses therein.
6. In a multiple fuse device, a body having individual explosion chambers, ducts leading from said chambers to an exhaust manifold, and one-way valves in said ducts which normally seal their respective chambers from the manifold, but which automatically open to connect their respective chambers to the manifold when the fuses in their respective chambers are blown.
7. In a multiple fuse device, a body having relatively isolated circumferentially spaced explosion chambers, fuses therein, a central exhaust manifold at the axis of the body, and radial ducts connecting said chambers to said manifold.
8. In a multiple fuse device, a circular body having relatively isolated circumferentially spaced explosion chambers, fuses therein, a central exhaust manifold at the axis of the body, and radial ducts connecting said chambers to said manifold.
9. In a multiple fuse device, a flat circular body having circumferentially disposed, relatively separated fuses on the flat sides thereof and adapted to be rotated successively into the operative station, and refusing means disposed on opposite sides of the flat body and operable automatically upon the blowing of a fuse, for rotating said body and placing into said station the next adjacent fuse.
10. In a multiple fuse device, a flat circular body having circumferentially disposed, relatively separated fuses on the flat sides thereof and adapted to be rotated successively into the operative station, and refusing means disposed on opposite sides of the flat body and operable automatically upon the blowing of a fuse, for rotating said body and placing into said station the next adjacent fuse and means for limiting the number of refusing operations that can occur automatically.
11. In a multiple fuse device, a fuse carrier comprising a substantially flat disc-like body of insulating material, and circumferentially spaced fuses projecting thru the body from side to side thereof and having exposed contact ends on the flat sides of the disc-like body, the body having a plurality of explosion chambers, one for that part of each fuse that is in the body, the chambers communicating with a center hole in the body that acts as an explosion manifold, and a hollow center-axis hub rotatably supporting said disc-like body, the interior of the center hole communicating with the interior of the hub.
12. In a multiple fuse device, a fuse carrier comprising a substantially flat disc-like body of insulating material, and circumferentially spaced fuses projecting thru the body from side to side thereof and having exposed contact ends on the flat sides of the disc-like body, the body having a plurality of explosion chambers, one for that part of each fuse that is in the body, the chambers communicating with a center hole in the body that acts as an explosion manifold, and a hollow center-axis hub rotatably supporting said disc-like body, the interior of the center hole communicating with the interior of the hub, gases from the explosion chambers venting thru said hub.
13. In a multiple fuse device, a fuse carrier comprising a substantially flat disc-like body of insulating material having thru slots connecting the flat sides of the body, fuses having their central parts in said slots and having exposed contact ends projecting therefrom and lying on the flat sides of said body, the slots extending radially from a large center thru hole in said body, and discs of insulation on the flat sides of said body forming side closures for said slots and retainers for said fuses, the edges of the discs meeting on the periphery of the body and being bound by a channelled ring provided with desirable indicia.
14. In a multiple fuse device, a fuse carrier comprising a substantially flat disc-like body of insulating material having slots connecting the flat sides of the body, fuses having their central parts in said slots and having exposed contact ends projecting therefrom and lying on the flat sides of said body, the body having bosses on its flat surfaces over which said contact ends are disposed so as to project beyond the major parts of the surfaces of the body sides.
15. In a multiple fuse device, a fuse carrier comprising a substantially flat disc-like body of insulating material having radial slots connecting the flat sides of the body, fuses having their central parts in said slots and having exposed contact ends projecting therefrom and lying on the flat sides of said body, the body having bosses on its flat surfaces over which said contact ends are disposed so as to project beyond the major parts of the surfaces of the body sides, and discs of insulation on the flat sides of said body forming side closures for said slots and retainers for said fuses, the bosses and the contact ends of the fuses projecting through and being exposed through holes in said discs, the edges of the disc holes clamping said fuses around said bosses and serving as barriers between the contact ends of the fuses and the parts thereof disposed in the slots.
16. In a multiple fuse device, a circular body having a central hole, two series of radial through slots, one series extending outwardly from said hole, and one series extending inwardly from the periphery of said body, fuses in said slots having contact ends on the faces of said body, an insulating covering on the periphery of said body for enclosing said slots and the parts of the fuses therein, the covering being clear of the body so that the slots of the outer series are in relative communication through the annular clearance, the ends of the fuses in one series overlapping the ends of the fuses in the other series, so that the two series of fuses are in multiple connection.
17. In a multiple fuse device, a circular body having a central hole, two series of radial through slots, one series extending outwardly from said hole, and one series extending inwardly from the periphery of said body, fuses in said slots and having contact ends on the faces of said body, an insulating covering on the periphery of said body for enclosing said slots and the parts of the fuses therein, the covering being clear of the body so that the slots of the outer series are in relative communication through the annular clearance, the insulating covering including discs on the faces of said body enclosing both series of slots and confining therein both series of fuses.
